F. H. SAUER.

AIR VALVE.

APPLICATION FILED MAR. 12, 1909.

927,603.

Patented July 13, 1909.

UNITED STATES PATENT OFFICE.

FREDERICK H. SAUER, OF NEW YORK, N. Y.

AIR-VALVE.

No. 927,603.

Specification of Letters Patent.

Patented July 13, 1909.

Application filed March 12, 1909. Serial No. 483,085.

To all whom it may concern:

Be it known that I, FREDERICK H. SAUER, a citizen of the United States, residing at New York city, in the county of New York 5 and State of New York, have invented certain new and useful Improvements in Air-Valves, of which the following is a specification.

The invention relates to improvements in 10 air valves, and has particular reference to that class of air valves utilized in connection with systems of steam radiation.

The object of the invention is to provide 15 means associated with the operative parts of the device, for draining water of condensation from the interior recesses of the valve structure by capillary attraction.

In the following is described in connection 20 with the accompanying drawings, one embodiment of the invention, the features thereof, being more particularly pointed out hereinafter, in the claims.

In the drawing, Figure 1 is a vertical sectional view of a radiator column, illustrating 25 in connection therewith, the manner in which the valve is mounted thereon; Fig. 2 is a side elevation of parts being shown in a longitudinal section of the valve draining means; and Fig. 3 is a detailed front elevation 30 of the valve draining means.

Similar numerals of reference indicate similar parts throughout the several views.

In the drawing, 1 indicates the conventional outline of a single or series of radiator 35 columns, having suitably formed therein, a bore 2, adapted to receive threaded nipple 3 formed on the body or base casting 4 of valve 5. Said body 4 has formed thereon, a threaded shoulder 6 and has mounted 40 therein, casing 7 inclosing the operative parts of the valve. Said casing 7 has formed on its upper end a threaded opening 8 adapted to receive adjusting screw 9 which has formed therein an air duct 10, said air 45 duct 10 comprising the means of forming a passage or means of communication with atmosphere, and the interior recesses of said valve 5. The upper exterior end of said casing 7 is threaded as at 11, and receives 50 at that point, cap 12, provided with a vent hole 13, connecting direct with air duct 10. Said base casting 4 has centrally formed therewith a shoulder 14, having also formed therewith a lug 15, the object of said lug 55 15 being hereinafter described. 16 indicates a stem of any suitable material such as vul-

canite, hardened rubber or other material, having the qualities of expansibility and has suitably cut therein a central longitudinal bore 17, the lower end of which rests 60 on shoulder 14 and surrounds lug 15; the upper end of said stem 16 is formed in any suitable shape and has mounted thereon an inverted float 18 having mounted therein at its upper end as at 19 a depending conical 65 shaped pin 20 and on its extreme upper surface an appending pin or lug 21, provided with a needle valve surface 22, adapted to seat itself within valve seat 23 in air duct 10, when the parts of said valve have 70 expanded a pre-determined distance to close the passage from the atmosphere to the interior recesses of said valve. Said nipple 3 or inlet and outlet connection may be of 75 any suitable length and may project within the column of the radiator, any suitable distance and is provided with an internal bore 24 having mounted therein a draining stem 25, said stem 25 comprises a horizontal 80 bar having formed therewith, an enlarged lug 26 provided with an air port or passageway 27, running horizontally through the core of said lug, and then extending upwardly in draining stem head 28, communicating with the interior recesses 29 of valve 85 5. Said draining stem 25 as above described comprises a horizontally extending rod 30, having its outer end bent downwardly as at 31, and has formed on its extreme lower end a drip point 32. Said horizontal body 90 30 has cut therein a slot 33, communicating with groove 34 which extends along both sides of said horizontal body to a point below the center of the bend at the outer end of said depending body. The body of 95 said horizontal stem and lug 26 is of a smaller diameter than the interior bore 24 of nipple 3 forming on both sides of said draining stem, fluid passageways 35, communicating with the interior recesses of the 100 radiator columns 1 and also the interior recesses of valve 5.

Core 26 described above as having formed therein an air port or passageway may be grooved as shown in dotted lines at 36 in Fig. 3 of the drawings, said groove acting in this instance as an independent air passageway. Expandible stem 16 is loosely guided by shoulders 14 and conical shaped depending lug or pin 20, providing means adapted to permit of a free radial or lateral movement of said stem 16 during the ex- 110

pansion of the interior parts of valve 5. Said depending lug 20, is as described conical in shape the object of the same being to provide means for the ready and quick 5 assembling of the device.

Drip stem 25 is of a smaller diameter than the interior bore 24 of nipple 3 providing means of permitting the free movement of said stem, vertically within said bore 24 and laterally within the body of the valve, owing to the space 37 between head 28 and the outer wall of said expandible stem 16. The depending end of said drip stem is somewhat heavier than the inner end and when 10 mounted on a radiator column will be free to swing in a greater diagonal plane than it would in case said stem 25 was designed to fit rigidly within said bore 24, the object being to provide means for assisting the 15 principle of capillary attraction in the draining of the water of condensation from the interior recesses of valve 5.

The operation of the device is as follows: The exhausting from the valve of the water 25 of condensation is on the principle of capillary attraction, as when the valve head is open to the atmosphere and when the fluids enter the valve body from the radiator, said stem 25 will start to sweat or moisture will 30 accumulate thereon and act as a means of collecting and draining of water of condensation from said valve, thus rendering the operative parts of said valve inapt to become chocked or sealed. Drip stem 25 as 35 shown and described provides separate and independent passageways for the fluids entering from the means of radiation and atmosphere and the draining of said valve.

What I claim and desire to secure by Letters Patent of the United States is:

1. An automatic air valve for radiators comprising a casing, a base for said casing, radiating means, said casing having a passage in the lower portion thereof forming 40 communication with said radiating means, said casing also having a vent port therein, 45

a valve controlling said port, a float mounted in said casing adapted to control said valve, an expansion column adapted to move radially and laterally in said float and to 50 control said valve, and a draining stem free to move radially and laterally in said passage provided with an independent air port formed in the upper body portion thereof, the lower body portion of said stem being 55 slotted and grooved to assist the draining of said valve of the water of condensation by capillary attraction.

2. An automatic air valve for radiators comprising a casing, a base for said casing, radiating means, said casing having a passage in the lower portion thereof forming communication with said radiating means, said casing also having a vent port therein, a valve controlling said port, a float mounted in said casing adapted to control said valve, an expansion column adapted to move radially and laterally in said float and to 60 control said valve, and a draining stem free to move radially and laterally in said passage provided with an independent air port 65 cut horizontally and vertically in the upper body portion thereof, the lower body portion of said stem being slotted and grooved to assist the draining of said valve of the water 70 of condensation by capillary attraction.

3. A device of the character described including a draining stem for automatic air valves comprising a longitudinally extending arm bent downwardly at its outer end 80 and having formed in the upper portion thereof an independent air port, the lower body portion of said stem being slotted and grooved for the purpose set forth.

In testimony whereof I have hereunto 85 signed my name in the presence of two subscribing witnesses.

FREDERICK H. SAUER.

Witnesses:

Wm. H. GARDNER,
